UNITED STATES PATENT OFFICE.

CHRISTOPHER P. SWEETMAN AND CHARLES M. PICCARD, OF DAYTON,
OHIO.

DESIGN FOR AN EMBLEM FOR THE ANCIENT ORDER OF HIBERNIANS.

SPECIFICATION forming part of Design No. 12,927, dated May 9, 1882.

Application filed January 3, 1882. Term of patent 7 years.

To all whom it may concern:

Be it known that we, CHRISTOPHER P. SWEETMAN and CHARLES M. PICCARD, both of Dayton, Montgomery county, Ohio, have invented a new and useful Design for an Emblem for the Ancient Order of Hibernians, of which the following is a specification.

Reference being had to the accompanying drawings, forming part of same, Figure 1 is the center portion of the emblem, and Fig. 2 represents the emblem complete.

Our invention relates to the shape and style of an emblem of circular form, in the center of which is a shield whose projecting points are set off with a shamrock-leaf. The top part has the letters "A. O. H." and directly under these is a sunburst and mountains. Next comes the clasped hands, with the Irish harp and leaves of shamrock on each side filling up the lower part. A number of parallel lines run from side to side, commencing under the mountains and down. Encircling the shield are two double-lined circles, between which are the words "Friendship, Unity, True Christian Charity, U. S. A." Between the inner circle and shield the space is filled up with fine

parallel lines. Surrounding these are heavy and light circular lines. An outer circle of double lines is formed in the same manner, except the heavy line is on the outside, around which are rays of alternate short and long lines.

We do not confine ourselves to the use of the emblem as a whole, as shown in Fig. 2, but the shield in the center thereof may be detached and used separately, as shown in Fig. 1.

Having thus described our invention, what we claim as new, and desire to secure by Letters Patent, is—

1. The design for an emblem, consisting of the two parallel circles surrounded by rays and inclosing the shield bearing the devices, all substantially as herein shown and described.
2. The design for an emblem, consisting of the shield bearing the devices, all substantially as herein shown and described.

CHRISTOPHER P. SWEETMAN.
CHARLES M. PICCARD.
